WILLIAM H. KLOCHE, OF WOODHAVEN, NEW YORK, ASSIGNOR TO THE CLEVELAND GRAPHITE BRONZE COMPANY, OF CLEVELAND, OHIO, A CORPORATION OF OHIO

METHOD OF MAKING SHEET-METAL BEARINGS

Application filed November 1, 1928, Serial No. 316,472. Renewed May 29, 1930.

The present invention, relating, as indicated, to a method of making sheet metal bearings, is particularly directed to an improved method of progressively forming a sheet or strip of rolled sheet bearing metal into a cylindrical bearing while maintaining the blanks at all stages of their formation as a part of the strip until the completion of the bearing, when the bearing is severed from the strip. The present method presents numerous advantages, including those of greater economy and speed of operation, greater accuracy in the feeding of the blanks at various stages to the next succeeding dies, and the avoidance of loss through inaccuracy of alignment of the blanks with the dies.

To the accomplishment of the foregoing and related ends, said invention, then, consists of the means hereinafter fully described and particularly pointed out in the claims; the annexed drawings and the following description setting forth in detail one approved method of carrying out the invention, such disclosed mode, however, constituting but one of the various ways in which the principle of the invention may be used.

In said annexed drawings:—

Fig. 1 is a plan view of a strip of sheet metal from which bearings may be formed by my improved method; Fig. 2 is a transverse section of the same on the line 2—2, Fig. 1; Fig. 3 is an end elevation of a finished bearing formed from the sheet of Figs. 1 and 2; Fig. 4 is a side elevation of the same; Fig. 5 is a view in side elevation of the strip when undergoing the various steps of the present process; Fig. 6 is a plan view of the same; Figs. 7, 8, 9, 10, 11 and 12 are transverse sections on the lines 7—7, 8—8, 9—9, 10—10, 11—11 and 12—12 of Fig. 6, respectively; Fig. 13 is a transverse section showing one form of trimming dies employed in the initial operation of the present method, Fig. 14 is a similar view illustrating one form of shearing dies; Fig. 15 is a similar view showing one form of initial bending dies; Fig. 16 is a similar view showing one form of forming dies; and Fig. 17 is a similar view showing finishing dies.

Cylindrical bearings are now made from

rolled sheet metal in large quantities, the process commonly used consisting in first cutting rectangular blanks from a sheet of metal, then forming these in one machine into substantially a U-shape and then finishing this U-shaped blank into a cylindrical blank and then finishing this U-shape blank into a cylindrical blank in either one or two subsequent operations. It has not been found practical to carry out these various operations successively in a single machine because of the difficulty of registering the partially formed blanks accurately in the dies and at the same time preventing the collecting on the blanks at various points of chips and pieces of metal, which, under the dies, causes spoiling of the blanks. It will be understood that to avoid the collecting on the blanks of chips and pieces of metal a strong air blast is employed. This air blast is required to be so strong in relation to the weight of the individual blanks, which are often of thin sheet metal, that the blanks are liable to be displaced and misaligned with respect to the dies. For these reasons the manufacture of cylindrical bearings from relatively light thin sheet metal stock has up to this time been carried out entirely in separate stages and in separate machines. The present method has been developed to permit the manufacture of such bearings in progressive stages in a single machine while avoiding the possibility of spoiling of the articles through misplacement in the dies. This method consists, briefly stated, in passing through a series of dies arranged progressively in a single machine, a strip of stock, initially trimming this stock, then transversely shearing it to partially separate the blank to be formed from the remainder of the strip, and then forming this blank into open cylindrical form while still a part of the strip proper and finally shearing it and practically simultaneously finishing the forming by bending the severed blank into true cylindrical form.

In Fig. 1 I have shown a strip of flat rolled sheet metal stock 1 of a suitable bearing metal, such for example as an alloy of copper and zinc, copper, tin and zinc, or similar material which is to be formed into the cylindri-

cal shape shown in Figs. 3 and 4. In carrying out the process this strip 1 is first trimmed to the desired transverse dimension by means of suitable dies, which are shown in Fig. 13, 5 and which cooperate to shear the two edges of the blank, or if desired a single edge, to bring the width of the blank to the required dimension. The strip 1, having a sheared portion 2, is then moved longitudinally 10 through the dies and is next operated on by the shearing dies 5, 5' (see Fig. 14) to partially shear the blank from the remainder of the strip, leaving the central portion 6 still uncut to connect the blank 3 with the main 15 strip. This partially sheared blank is then moved to the next station, where it is operated upon by the bending dies 7, 7' (see Fig. 15) to form the strip as shown in Fig. 10, in which the outer edges 8 are bent downwardly 20 out of the normal plane of the strip while the blank in this form is still connected to the strip proper and to the next blank by means of a central unsheared portion 6.

The blank in the form of Fig. 10 is then 25 moved to the succeeding station where it is operated on by the dies 9, 9' and over the mandrel 40, (see Fig. 16) to form it into substantially U-shape with the lower ends 10 bent inwardly slightly to facilitate the final 30 forming operation, and at this stage the blank is still connected to the next succeeding one by the same unsheared portion 6.

The final operation, which takes place upon 35 the movement of the blank to the next station, consists in the shearing through of the connecting portion 6, during which action the final forming dies 11, 11' (see Fig. 17) engage the blank and finish the forming of the bearing by bending the U-shaped blank 40 of Fig. 11 into the truly cylindrical blank shown in Fig. 12 about a mandrel 13 which is inserted within the blank of Fig. 11 at the same time that this blank is sheared from the strip proper.

45 The last two operations of forming the cylindrical bearing involve not only the forming but also the swaging and setting of the metal so that there is no tendency for the finished cylindrical element to open, or for 50 the abutting edges to spread. This action is effected by the swaging of the metal in the final operation and by the initial bending inward of the adjacent edges which is effected in the dies shown in Fig. 15.

55 By forming the bearings in the manner just described it is impossible for any misalignment between the blank at any stage and the dies to occur. The blank is at all times, up to the very final forming step, an integral 60 part of the entire strip and is positioned and aligned by reason of this connection. During all the operations a strong air blast from the nozzle 14 can be forced across the strip, thus removing all of the chips and particles 65 of metal from the surfaces of the blank as it

progresses without in any way misplacing the blank or causing it to chatter or move in the dies by reason of the integral connection between all portions of the strip as it passes through the dies.

70 Other modes of applying the principle of my invention may be employed instead of the one explained, change being made as regards the process herein disclosed, provided the step or steps stated by any of the 75 following claims or the equivalent of such stated step or steps be employed.

I therefore, particularly point out and distinctly claim as my invention:—

1. In a method of making bearings, the 80 steps which consist in partially shearing a blank from a sheet of metal, forming such blank into open channel form while still integrally united with said sheet, and then severing such blank and forcing the same 85 into closed cylindrical form.

2. In a method of making bearings, the 90 steps which consist in partially shearing a blank from a sheet of metal, forming such blank into open channel form while still integrally united with said sheet, and then severing such blank from said sheet and forcing the same into closed cylindrical form.

3. In a method of making bearings, the 95 steps which consists in partially shearing a blank from a sheet of metal, forming the same by transversely bending into open, channel form, and then severing such blank from said sheet and forcing the same into closed cylindrical form.

4. In a method of making bearings, the 100 steps which consist in partially shearing a rectangular blank from a sheet of metal by transversely cutting the same, forming such blank into open channel form while still 105 integrally united with said sheet, and then severing such blank from said sheet and substantially simultaneously forcing the same into closed cylindrical form.

5. In a method of making bearings, the 110 steps which consist in partially shearing a rectangular blank from a sheet of metal by transversely cutting the same, forming such blank into open channel form while still 115 integrally united with said sheet, gripping said blank between final cylindrical forming die members, severing the same from said sheet and then causing said final die members to force said blank into closed cylindrical form.

6. In a method of making bearings, the 120 steps which consist in partially shearing a rectangular blank from a rolled sheet of metal by transversely cutting said metal and leaving an unsevered portion equal in length 125 to not less than one-third the final diameter of the desired bearing, then transversely bending the severed portion of said blank into channel form, and finally completely forming said blank by bending into closed 130

cylindrical form and severing the same from said sheet.

7. In a method of making bearings, the steps which consist in partially shearing a rectangular blank from a rolled sheet of metal by transversely cutting the metal and leaving an unsevered portion equal in length to not less than one-third the final diameter of the desired bearing, then initially bending inward the ends of said severed portions, forming such blank into channel forms with the curved ends projecting inwardly toward the center of such channel, and completely forming such channel into a cylindrical form and severing the same from said sheet.

8. In a method of making bearings, the steps which consist in partially shearing a rectangular blank from a rolled sheet of metal by transversely cutting the metal and leaving an unsevered portion equal in length to not less than one-third the final diameter of the desired bearing, then initially bending inward the ends of said severed portions, forming such blank into channel forms with the curved ends projecting inwardly toward the center of such channel, and completely forming such channel blank into cylindrical form between swaging dies to set the metal of the blank in the desired form.

30 Signed by me, this 27th day of October, 1928.

WILLIAM H. KLOCKE.
